CHARLES VOGEL, OF NEW YORK, N. Y.

Letters Patent No. 74,868, dated February 25, 1868.

IMPROVED TRIP-HAMMER.

The Schedule referred to in these Letters Patent and making part of the same.

TO ALL WHOM IT MAY CONCERN:

Be it known that I, CHARLES VOGEL, of the city, county, and State of New York, have invented new and useful Improvements in "Trip-Hammers;" and I do hereby declare that the following is a full and exact description thereof, which will enable those skilled in the art to make and use the same, reference being had to the accompanying drawings, and the letters of reference marked thereon.

The present invention consists, first, in a novel connection between the shank or stem of the hammer-head and the beam, through which the hammer-head is tripped; second, in so constructing the beam carrying the hammer-stem or shank that it can be adjusted for raising the hammer-head to a greater or lesser height; third, in a novel combination and adaptation of springs for imparting additional force and strength to the blow of the hammer, their combination and arrangement being such as to be susceptible of adjustment for a blow of greater or lesser degree of force and strength; fourth, in a novel arrangement of parts for arresting the motion of the hammer without requiring the driving-mechanism to be stopped, the arrangement being such as to be self-operating, when set free, and to arrest the hammer, when at or near the end of its upward stroke or movement, and there hold it, leaving the anvil exposed; fifth, in an arrangement of parts upon the driving-shaft of the trip-hammer, on which they are hung, to swing about and over its driving-pulley, in combination with a treadle, or other suitable operating-lever, for the purpose of enabling the driving-belt to be more or less tightened about the driving-pulley, as may be desired or found necessary in the running of the hammer. In the accompanying plate of drawings, my "improvements in trip-hammers" are illustrated—

Figure 1 being a partial side elevation or view and vertical section of a trip-hammer constructed according thereto,

Figure 2 a plan or top view, and

Figure 3 a detail view.

A, in the drawings, represents a framework, carrying the several parts, to be hereinafter described, composing a trip-hammer, arranged to embrace the several features of the present improvements.

This framework A consists of two similar-shaped upright frames, B, made of the general outline and shape shown in the drawings, and braced in position, at the proper distance apart, by brace-rods C, at suitable points, and at their lower ends, D, properly constructed for being bolted or otherwise fastened to a floor, or other fixed surface.

These frames B, at the outer ends to their lower extension-pieces E, are joined and fastened to a common block, F, that, upon its upper surface, G, is adapted to receive the anvil-block H, on which the hammer of the machine is to drop and act. Over this anvil-block H, but at a proper distance above, the upper arms I to the side-frames B extend, and are there joined together by a common cross-head, J, suitably constructed for a stem or shaft, K, to move in a vertical plane, which stem, at its lower end, L, carries and has properly fixed to it the hammer-head M.

To this hammer-stem K the cross-head J forms one guide, in its upward and downward movement, but to more perfectly and steadily guide it, another guide, N, is provided, that, by uprights O, is supported in position directly above the said cross-head J.

P, a cross-arm to upper end of hammer-stem K, above its upper guide N. To the outer ends of this cross-arm P, and upon each side of the hammer-stem K, is hung the upper end of similar connecting or pitman-rods Q, that, being extended down along and upon the sides of the hammer-stem, are, at their lower ends, hung to the outer ends of the angular arms R, at the front end to the beam S, fixed to a shaft, T, arranged to turn in bearings of the side-frames B, across from one to the other of which it extends on a horizontal plane. This beam S is extended to the rear of its shaft T, and at such end is provided with a block, U, having slots V, through which the screw-bolts W pass, that are used for fastening such block to the beam. By means of these slots V, the block U is susceptible of adjustment upon the beam S, in the direction of its length, and thus the end X to such block, made to project more or less to the rear of the shaft T, for being acted upon by the trip-cam or arm Y, fixed to the driving-shaft Z. This driving-shaft Z is arranged to turn in bearings of the side-frames B, across from one to the other of which it extends in a horizontal plane, and, at one end, has a balance-wheel, A², and a flange-pulley, B², around which a belt from the driving-power is passed.

From the above description of the arrangement of parts, it is plainly shown that, by the turning of the driving-shaft Z in the proper direction, the hammer will be lifted or raised up, through the action of the cam or arm Y of such shaft, upon the beam to which the hammer is connected, until, by the continued turning of the shaft Z, its cam has passed by the said beam, when the hammer is then free to fall, from its own weight and

gravity, to the anvil-block, and upon whatever substance may be there placed for being hammered by it; and that, also, as the block to the beam carrying the hammer is susceptible of adjustment upon the said beam, the height to which the hammer is to be raised may be varied or made more or less within certain limits by simply projecting such block either more or less into the plane of rotation to the tripping-cam or arm of the driving-shaft.

Around the rocker-shaft, to which the beam is secured, carrying the hammer, and upon each side of such beam, is a similar coiled or spiral spring, D², that are both extended by their end the nearer to the beam, toward the plane of movement of the hammer, resting upon the cross-arm E², to a bolt, F², secured in the beam S by a screw-nut, G², and by their end the farther from the beam, to and upon the grooved rests H², fixed to a common horizontal transverse shaft, I², of the side-frames B.

This shaft I² is arranged to turn in the frames B, and for turning it, a hand-wheel, J², is provided, working through a tubular shaft, K², to which it is secured, that has a worm-gear, L², working into a pinion, M², of the said shaft I². The tubular shaft K² is hung in suitable bearings of the framework A.

By the above-described arrangement of springs D², which rest upon the beam carrying the hammer, and upon the rests of the shaft I², it is plainly manifest that, in the raising of the hammer, they will be, to a greater or lesser extent, the more tightly coiled thereby, according to the relative positions of the rests with regard to the movement of the hammer, and thus, when the hammer is left free to fall, in uncoiling, made to impart a corresponding amount of additional force or strength to its blow.

To increase or decrease this action of the springs, their rests are susceptible of adjustment, those upon the beam by simply raising or lowering the cross-arm, through the turning of the screw-nut, and the others, that are upon the shaft I², by turning such shaft in the proper direction to either throw them up or down, as the case may require.

A⁴, a pulley, arranged to slide on the driving-shaft, between its cam-trip and one of the side-frames B. This pulley A⁴ is equal, or nearly so, in diameter to that of the largest circle described by the said cam, as the driving-shaft revolves, so that, if placed in position upon the tripping-end of the hammer-beam, to bear against it when the hammer is up, it will not allow the hammer to fall to the anvil, or, in other words, it will prevent all action of the trip-cam upon the hammer-beam.

This pulley A⁴ is provided with a collar, B⁴, upon its outside face. This collar B⁴ is grooved around its periphery, and in such groove C⁴ the outer ends to a forked-shaped arm, D⁴, are located, which arm D⁴, by its common shank E⁴, is fastened to one end of a rod, F⁴, that is extended through the tubular shaft K², herein-before referred to, and at the front end to such tube, provided with a handle, G⁴, for convenience in turning it, and thus, by means of such turning, slide the said pulley A⁴ either toward or away from the plane of action of the hammer-beam, as may be thought necessary.

To this handle G⁴ a spring-pawl, H⁴, is hung, to engage with the notch I⁴ of the arm J⁴, and to thus hold the pulley out of the plane of action of the hammer-beam, when, as such pawl is released, a spiral spring, K⁴, is properly arranged to slide the pulley into the plane of movement to the hammer-beam the instant it is brought to the proper point by the action of the trip-cam, to allow it to pass by.

From the description above of the arrangement and operation of parts for stopping the movement of the hammer-beam, it is plain to be seen that it is not necessary to arrest the driving-mechanism, nor to throw the driving-shaft to the trip-hammer out of connection therewith, and that, furthermore, they are self-operating, when set free for action, and are so arranged as to hold the hammer at or near its highest point of elevation, thus leaving the anvil-block free to the workman for arranging the work thereon, or for any other purpose.

A⁵, a frame, hung upon the driving-shaft, so as to turn thereon, and to swing over its driving-belt pulley. This frame carries a roller, B⁵, at one end, for the action upon the driving-belt, as the frame is swung up into a vertical position, to tighten it about the pulley, either more or less, according as it is made to approach either more or less near to a vertical position.

C⁵, a rod, connecting frames A⁵ with one end; to a treadle-frame, D⁵, hung upon a fulcrum, E⁵, of the side-frames B. This treadle-frame extends around the front end of the framework, and at such portion is suitably flattened for the reception of the prop to depress it to a greater or lesser extent, a stop, F⁵, being hung to the anvil-block holder, in position for being swung to hold the treadle down, when desired.

When the prop or stop, or both, are released from the treadle, the belt-tightener, which is attached, resumes its horizontal position, in doing which, springs K⁵ are provided to assist and facilitate the same.

Having thus described my invention, I claim as new, and desire to secure by Letters Patent—

1. The bars or rods Q, secured to the cross-head P of the hammer-stem K, when said rods are attached to the angular arms R, upon the front end of the beam S, as herein shown and described.
2. The block U, provided with the cam-shaped end X, when adjusted upon the beam S, by means of the slots V and screw-bolts W, as herein described, for the purpose specified.
3. The arrangement of the sliding pulley A⁴, or its equivalent, with the block U, and with the operating-beam of the hammer, substantially as described, for the purpose specified.
4. The tightener-frame A⁵, bearing in one end the driving-pulley B⁵, arranged with the connecting-rods C⁵, curved treadle D⁵, and spring K⁵, as herein described, for the purpose specified.

The above specification of my invention signed by me, this 20th day of August, 1867.

CHARLES VOGEL.
